(57) **CLAIM**

The ornamental design for a relay holder, as shown and described.

DESCRIPTION

FIG. 1 is a rear elevational view of the relay holder;
FIG. 2 is a front elevational view thereof;
FIG. 3 is a left side elevational view thereof;
FIG. 4 is a top plan view thereof;
FIG. 5 is a right side elevational view thereof;
FIG. 6 is a bottom plan view thereof; and,
FIG. 7 is a front perspective view of the relay holder.
The broken lines are included for the purpose of showing
portions of the relay holder that form no part of the claimed
design.
